UNITED STATES PATENT OFFICE.

ALFRED AUGUSTUS SANDBROOK, OF LONDON, ENGLAND.

LAMP.

Application filed July 23, 1923. Serial No. 653,350.

To all whom it may concern:

Be it known that I, ALFRED AUGUSTUS SANDBROOK, a subject of the King of England, residing in the city of London, in the 5 Kingdom of England, have invented new and useful Improvements in or Relating to Lamps, of which the following is a specification.

The invention relates to lamps having an 10 opaque resilient lamp body of rubber or other resilient or flexible material capable of resisting crushing effects, and one object of my invention is to render such resilient lamps inflatable, without interference of the 15 emission of light, so as to impart increased steadiness and to avoid the necessity of stiff heavy and consequently expensive rubber lamp bodies.

Another object is to provide a comparatively thin and light resilient lamp body with one or more inflatable bladders.

A further object is to provide means preventing the bladder or bladders from pushing a reflector and the lens out of the aperture for the emission of light.

Another object is to provide strengthening means for seating the reflector and lens in the aperture.

Another object is to provide a resilient lamp with a plurality of bulbs, reflectors, lenses and bladders.

These and other minor objects will become apparent from the following specification and appended claims and from the detailed description of the accompanying drawings, in which:

Figure 1 is a vertical central section of an inflatable resilient lamp provided with means for inflating the lamp body; Fig. 2, a 40 vertical section of a resilient lamp fitted with a bladder; and Fig. 3, a transverse section of a resilient lamp having four bulbs, four reflectors, four lenses and a centrally located bladder which may be formed as a single part to fit behind the reflectors, or in four appropriate sections.

In these drawings, A is the outer opaque resilient body having a reinforced or other edge C to carry or hold the glass or lens B, and provided with a reflector K opposite said glass B. The reflector K may carry the bulb-holder and bulb D, the electrical leads D¹ therefore passing advantageously through an air-tight connector D^x fast on the lamp

A. I also provide a non-return valve G 55 through which the body A may be inflated.

Means are of course provided by which the lamp can be secured to a vehicle and since these are of known and usual construction, they have been omitted from the drawing for 60 the sake of simplicity.

In Fig. 2 the same reference letters denote the same parts. However, the outer body A of the lamp is provided with an inner inflatable bladder J and a reflector K 65 in front of said inflatable bladder. As it may not always be convenient to inflate the bladder through a non-return valve, any other suitable means may be adopted so as to better suit particular requirements. For 70 example the gaseous fluid may be retained in the simple manner used in respect of football bladders.

In the construction shown at Fig. 3, the opaque resilient body A¹ is formed with 75 four cavities E each containing a reflector K and bulb D and being covered by a glass or lens B as before stated. At the rear of the reflectors K is disposed the inflatable bladder L. This bladder L may have small 80 cavities E¹, reinforced by ribs or rigid fittings, cups or the like F for housing the bulb-holders for the electric bulbs D.

The inflatable bladder L may however be made in several separate parts or sections, 85 four being indicated by the dotted lines L¹ and one or all being inflatable together or separately through non-return valves (not shown), or otherwise as desired.

The leads for the electric light bulbs are 90 passed through the bladder or bladders in any appropriate and air-tight manner. They may for instance follow the positions of the dotted lines.

I claim:—

1. An opaque resilient inflatable lamp capable of emitting direct rays of light, a bulb carried in the interior of the lamp, a reflector at the rear of the bulb, an air-tight connector fast externally to the lamp, electrical leads extending from the bulb in an air-tight manner through the connector, and inflating means fast to the body of the lamp.

2. An opaque resilient inflatable aper- 100 tured lamp body capable of emitting light, 105 inflatable means disposed within the body of the lamp, reflecting means fast in the

22
apertured lamp body and in rearward contact with said inflatable means, light-giving means fitted to the reflecting means, and transparent closing means forward of said

reflecting means. shaped inflatable bladders to fit the interior of the lamp body between the spaced reflectors.

15

3. An opaque practically globular and apertured resilient lamp body, a plurality of spaced concave reflectors fast in the apertured body, lenses for covering said reflectors, bulbs mounted in the reflectors, cups fast to the rear of the reflectors, leads connected with the bulbs, and a plurality of
- 10
4. An opaque practically globular and apertured resilient lamp body, means for strengthening the rims of the apertured body, spaced reflectors and combined lenses engaged in the strengthening means of said 20 rims, bulbs mounted in the reflectors, and an inflatable bladder to fill the lamp body between the spaced reflectors.

ALFRED AUGUSTUS SANDBROOK.
